(William Hutton's Rotary Engine
Hutton's Patent)

The Schedule referred to in these Hutton's Patent (and making part of the same) containing a description in the words of the said William Hutton himself of his improvement in the mode or manner of applying the action and reaction of Steam for the purpose of obtaining a rotary motion applicable to machinery entitled "Hutton's Rotary Engine"

To all to whom these Presents shall come

Be it known that J. William Hutton of Geneva, Ontario County State of New York, Cabinet-Maker have invented a new and useful improvement in the mode or manner of applying the action and reaction of Steam for the purpose of obtaining a rotary motion applicable to machinery (and that the following is a full and exact description of the said improvement) in the mode or manner of applying the action and reaction of Steam as invented by me.

Description or Specification

The drawing herewith exhibited contains three figures viz: Figure 1. is a perspective view of "Hutton's Rotary Engine" Figure 2. is a section showing the hollow expansion hub, the channels in the arms, and rim of the wheel, Bush and orifices. Figure 3. represents a section parallel with the axis showing the hollow axis through which the steam is conveyed into the hollow hub. The following is the improvement in the mode or manner of applying the action and reaction of Steam for the purpose above mentioned. Note. The Roman letters A, B, C, &c. refers to those on the figures 1, 2, and 3, of the drawing herewith exhibited. A is a strong case made of iron or other suitable metal enclosing the wheel. B is an induction pipe of any suitable material for carrying steam directly into the hollow hub H through the hollow axis. It should be large enough to convey more steam into the hollow hub than can be discharged through the channels of the arms. C. describes H, the object being to allow the steam to expand and communicate a rapid motion thereby to the wheel at the direct economy of steam. Through the induction pipe B will go a valve, C. The

Sept. 18, 1834

exhaust pipe of any suitable metal to convey the steam from the case A into the outward air, or into a condensing tub. D. The rim of the wheel of any suitable metal of size in which there is a hollow diminishing from the arms P, to the orifices M. This hollow should be near to the inner edge of the rim, the periphery being solid. E. The hollow expansion hub of a conical form of any suitable metal and size sufficiently strong to bear a pressure of steam equal to that of the boiler used. F. The hollow arms (of the same substance as the wheel) springing from the hollow expansion hub affixed to the hollow rim D. These arms may be straight or curved, and any number may be used or added. G. Channels in the arms P, to be considerably larger say two thirds larger than the hollow in the rim of the wheel, and ending on buckets opposite to the orifice M. H. Hollow expansion hub of any suitable metal and size of a concave form. see B. I. Hollow axis connected with the box K. by means of screws or nuts, through which the steam is conveyed into the hollow hub H. K. Box of any suitable metal for the hollow axis I, to receive; which should be made sufficiently tight to prevent steam from escaping; & L. Pulley attached to the solid axis of the hub H. to which any required machinery may be attached, this pulley may be of any suitable matter and size. M. Orifices pierced through the rim of the wheel D, running diagonally at about 45 degrees from a line drawn through the centre of the hub H. to the rim of the wheel, the size of these orifices will depend on the power required to be given to the engine (and may be from $\frac{1}{16}$ of an inch to any size according to the power desired. The hollow of the hub, and channels of the arms and rim of the wheel will also be increased according to the power desired to be communicated. It is to be understood, that what I claim as my invention or improvement is the hollow expansion hub, together with the hollow wheel, by means of which the steam is confined until it is conveyed on to the tops or buckets over the hollow within the rim of the wheel, which causes the wheel to move in the same direction of the steam; all the manner in which the steam is discharged from the wheel, it being discharged in a contrary direction from that in which the wheel moves thereby obtaining

by the combination of the action and reaction, the assistance of the reaction so as to cause it to work in concert with the direct action. It is obvious that this improvement may be applied to machinery in any position; and it is therefore deemed unnecessary to specify more particularly the application than is seen in such a machine as the drawing herewith exhibited represents. It may be applied to mill (and other machinery) or to prospecting carriages on rail road, or on common roads. Philadelphia August 9th 1834.
